UNITED STATES PATENT OFFICE.

JAMES COWIN, OF MINNEAPOLIS, MINNESOTA.

SILO DOOR AND LADDER STRUCTURE.

Application filed May 5, 1926. Serial No. 106,987.

The object of my invention is to provide a silo door and ladder structure wherein the frame of the door serves to support the ladder elements and the door itself supports a ladder element which serves not only as a ladder element but also as means for locking and holding the door in closed position against the door frame.

Still a further object is to provide a silo door adapted to be locked in position by a step or ladder element and the greater downward pressure upon the ladder element, the tighter the door will be held in position.

Still a further object is to provide a silo door adapted to have mounted thereon the entire locking means wherein the door is held in closed position so that when the door is removed no obstructions will be had to interfere with the door opening.

With these and other objects in view, my invention consists in the construction, arrangement and combination of the various parts of my invention, whereby the objects contemplated are attained, as hereinafter more fully set forth, pointed out in my claims, and illustrated in the accompanying drawings, in which:

Figure 1, is a front view of a portion of a silo with my improved silo door and ladder structure installed thereon.

Figure 2, is a sectional view taken on line 2—2 of Figure 1.

Figure 3, is a horizontal sectional view taken on line 3—3 of Figure 1.

Figure 4, is a detail sectional view showing the connection between the door closing means and the door frame.

Figure 5, is a detail sectional view showing how the channel members of the door frame are connected together and

Figure 6, is a detail view of one end of the ladder element or closing means for the door.

In the accompanying drawings I have used the reference numeral 10 to indicate a silo of any type which may be either built up of blocks or cement staves, or any other suitable material.

My improved silo door and ladder structure includes a door frame 11 formed of a pair of vertically spaced uprights 12 and a pair of transverse connecting members 13 which are rigidly connected together for forming the entire rectangular door frame 11.

The members 12 and 13 are channel shaped

in cross-section and the ends of the same have their connecting webs bent and lapped over each other as clearly shown in Figure 5 of the drawings and are riveted together, thus giving me additional rigidity and strength for the entire door frame.

The flanges of the channel shaped members 12 and 13 may be arranged to abut against each other and only the connecting webs lap over each other as shown in Figure 5 of the drawings.

Fixed to the top and bottom ends of the upright members 12 are the bracket arms 15 and 16. The bracket arms 15 extend outwardly and downwardly from the lower end of the door frame 11 and the bracket arm 16 extends upwardly and outwardly from the door frame 11.

The spaced pairs of bracket arms 15 and 16 are connected together by ladder elements 17 which in the drawings I have illustrated as formed of angle material although any type of cross piece may be used and the cross pieces or ladder elements 17 serve as steps or a ladder element to climb up into the silo.

It will be noted that the ladder elements 17 as mounted upon the bracket arms 15 and 16 are spaced a considerable distance apart and it is necessary to have an intermediate step or ladder element and this is formed in connecting with the silo door itself in the manner I will now describe in detail.

A door 18 formed of metal or any other suitable material, is arranged to cover the entire door opening and to abut against the inner surface of the door frame 11.

The door 18 has fixed to it a pair of angle irons 19 which are extended lengthwise or vertical relative to the door and serve both to brace the door and as a means of connection to the closure member as well as the intermediate step or ladder element.

A yoke shaped member 20 serves as the intermediate ladder element and is connected to the door 18 by a pair of connecting arms 21 which are pivotally connected at one end to the upright angle irons 19 and adjustably connected at their other ends to the connected portion of the yoke member 20.

The legs 22 of the yoke member 20 are formed with slots or notches 23 in their free ends which coact with stud bolts or pins 24 mounted upon the uprights 12 of the frame 11.

The stud bolts or pins 24 serve as a pivot for the yoke member 20 and are mounted in the upright members 12 and held there by washers and nuts 25, clearly illustrated in Figure 4 of the drawings.

An enlarged head or nut 26 is also mounted upon the bolts 25 and the legs 22 are partially received between the nuts 25 and 26.

10 An additional flat plate 27 may be connected to the uprights 12 and this serves to reinforce and brace the stud bolts or pins 24.

The connection between the arms 21 and the angle irons 19 is slightly lower than the 15 position of the pins or stud bolts 24.

The yoke member 20 which is connected to the door 18 through the arms 21 is positioned with the slots 23 receiving the pivots or stud bolts 24 and thereafter downward 20 pressure upon the yoke member 20 will cause the door 18 to be drawn against the door frame 11 and the greater the downward pressure the tighter the door will be held against the door frame.

25 The positioning of the stud bolt 24 above the connection between the arms 21 with the angle irons 19 insures the yoke member to remain in its downward or locked position when the parts are placed under a tension.

30 In other words after the yoke member 20 is moved to the position shown in Figure 2 of the drawings, it would be necessary to overcome to a certain degree the tension applied to the door through the arm 21 when 35 the yoke member 20 would be raised.

The yoke member 20 and arms 21 are arranged upon different centers so that when the door is in closed position the parts will be "past center".

40 The connecting member of the yoke 20 between the legs 22 serve as a ladder element and this in connection with the ladder element 17 furnishes the entire ladder structure for the silo.

45 Stops 28 are mounted upon the uprights 12 and limit the amount of downward movement of the yoke member 20.

The tension applied upon the door when it is in closed position may be varied by 50 simply tightening or loosening the connections between the arms 21 and the yoke member 20.

The entire door and yoke member 20 may be disconnected from the door frame 11 by 55 simply raising the yoke member 20 and lifting the same upwardly until the notches or slots 23 clear the stud bolts 24.

60 It will be noted that when a series of door assemblies and door frames are used that a continuous latter will be formed from the two ladder elements mounted upon the door frame and the ladder element or closure element which is mounted upon the door itself and pivotally connected to the door 65 frame.

Some changes may be made in the construction and arrangement of the various parts of my invention, without departing from the real spirit and purpose of my invention and it is my intention to cover by 70 my claims, any modified forms of structure or use of mechanical equivalents, which may be reasonably included within their scope.

I claim as my invention:

1. A silo door and ladder structure including a frame for the door opening having ladder elements secured to its top and bottom sides, a door for said opening adapted to be engaged with the inner side of the door frame and means for holding the door in closed position, said last means including a yoke member pivotally connected to the door frame and loosely connected to the door and adapted when swung on its pivots to draw the door towards the door frame and to retain the door in its closed position, said last means when the door is in closed position serving as one step element of a ladder structure.

2. A silo door and ladder structure including a frame for the door opening having ladder elements secured to its top and bottom sides, a door for said opening adapted to be engaged with the inner side of the door frame and means for holding the door in closed position, said last means including a yoke member pivotally connected to the door frame and loosely connected to the door and adapted when swung on its pivots to draw the door towards the door frame and to retain the door in its closed position, said last means when the door is in closed position serving as one step element of a ladder structure and stops on the door frame for limiting the pivotal movement of the yoke member in one direction.

3. A silo door and ladder structure including a frame for the door opening having ladder elements secured to its top and bottom sides, a door for said opening adapted to be engaged with the inner side of the door frame and means for holding the door in closed position, said last means including a yoke pivotally supported upon the door frame and connected to the door, the pivot connection of the yoke member with the frame and the connection of the yoke member with the door being at spaced points so that pivotal movement of the yoke member in a downward direction will cause the yoke member to move past center relative to its connection with the door thereby maintaining the door in closed position.

4. A silo door and ladder construction comprising an outwardly opening channel shaped door frame, a door for said door frame designed to engage the inner side thereof, a yoke member having rods secured thereto which are pivotally connected to said door and means on said door frame to en- 130

gage the ends of said yoke whereby said yoke forms a lever for holding said door closed and serves as a step.

5. A silo door and ladder construction comprising a door frame, a door for said door frame designed to engage the inner side thereof, a yoke member having rods secured thereto which are pivotally connected to said door and means on said door frame to engage the ends of said yoke whereby said yoke ^{forms} a lever for holding said door closed and stops for limiting the lever movement of said yoke.

10. A silo door and ladder construction comprising a door frame having outwardly and upwardly extending arms from the top thereof and outwardly and downwardly extending arms from the bottom thereof, step

elements on said arms, a door for said door frame, a step comprising a yoke pivoted to ²⁰ said door frame between said first mentioned steps and having parts connected to said door for causing it to engage the inner surface of said door frame.

15. A device of the class described comprising a door frame having steps secured thereto adjacent the upper and lower ends thereof, an intermediate step pivotally and detachably secured to said door frame and having rods extending to a door for causing said door to engage the inner surface of said door frame, said intermediate step acting as a lever for securely holding said door thereagainst.

JAMES COWIN.
